W. L. BARRON,
METHOD OF ATTACHING GARMENT HOOKS TO FABRICS.
APPLICATION FILED OCT. 24, 1916.

UNITED STATES PATENT OFFICE.

WILLIAM L. BARRON, OF NEW YORK, N. Y., ASSIGNOR TO THE SINGER MANUFACTURING COMPANY, A CORPORATION OF NEW JERSEY.

METHOD OF ATTACHING GARMENT-HOOKS TO FABRICS.

1,354,795.

Specification of Letters Patent.

Patented Oct. 5, 1920.

Application filed October 24, 1916. Serial No. 127,374.

To all whom it may concern:

Be it known that I, WILLIAM L. BARRON, a citizen of the United States, residing at New York, in the county of New York and 5 State of New York, have invented certain new and useful Improvements in Methods of Attaching Garment-Hooks to Fabrics, of which the following is a specification, reference being had therein to the accompanying drawings.

In attaching the well-known garment-hooks to fabric material of various kinds it is customary to apply fastening means to the fabric across the hook-shank at the bottom 15 of the throat and additional fastening means through the usual eyes, the purpose being to fixedly secure the hook in position adjacent its longitudinal extremities and prevent displacement thereof relative to the fabric. In 20 practice, particularly when a machine is utilized, it is difficult to apply the fastening means at the bottom of the throat for the reason that the overhanging hook-bill interferes with the movement of the fastening 25 means to final position closely embracing the hook-shank.

It has heretofore been customary to hold the hook in attaching position with its back against the fabric and then to pass fastening means, in the form of ordinary stitches of thread, across the hook near the bottom 30 of the throat and through the fabric, deflecting the thread around the end of the hook-bill and into the throat as each stitch is 35 drawn down to final position. In constructing a machine for this work it is particularly difficult to provide means for deflecting the needle-thread around the end of the hook-bill with certainty and without breaking the 40 thread, especially when sewing on hooks of the larger sizes having long bills.

It has also been proposed to lay a first group of fastening stitches across the hook-shank immediately behind the eyes and then 45 relatively move the fabric and hook to slip the group of stitches to final position at the bottom of the throat before passing a second group of stitches through the eyes. The disadvantage of this method, however, is 50 that the first group of stitches must be loosely formed in order that it may subsequently be slipped over the "hump" usually found in the shank of a garment hook opposite the end of the bill.

55 One object of the present improvement is

to devise an improved method of attaching garment-hooks or similar hook-shaped fasteners to fabric, whereby the fastening means or stitches may be snugly applied across the shank at the bottom of the throat 60 in a direct manner, without the necessity of deflecting the thread around the end of the bill.

Further objects of the invention will appear from the following description and 65 claims.

In carrying my improved method into effect a garment-hook or other hook-shaped article is first held with its bend adjacent the fabric and with its throat directed preferably at right angles to the surface of the fabric. Fastening means, such as stitches of thread are next passed, without deflection, directly into the throat of the hook and into the fabric. The hook and fabric are 70 then relatively rotated about the fastening means as a hinge to position another part of the article, such as the eyes, adjacent the fabric, whereupon additional fastening means are passed about the article preferably through the eyes and into the fabric. 75

Although the proposed method is independent of any particular mechanism for carrying it into effect, it is deemed expedient to employ suitable mechanism and to this 80 end I, together with A. F. Fifield, have constructed a machine which is fully disclosed in a co-pending application Serial No. 92,136, filed April 19, 1916.

In the accompanying drawings, Figure 1 85 is a perspective view of the work-holder of said machine for carrying the proposed method into effect. Fig. 2 is a perspective of the clamping jaws and fabric supporting plate showing a garment-hook and a piece of 90 fabric held thereby. Fig. 3 is a view illustrating the first step of the improved method and showing how the hook is to be held relative to the fabric so that the initial fastening means may be passed directly 95 into the throat of the hook and into the fabric. Fig. 4 is a view showing the relative positions of the hook and fabric during the latter part of the attaching operation, and Fig. 5 is a view of the hook attached 100 to the fabric.

In the accompanying drawings, 1 indicates a work-holder of the well-known type disclosed in the United States patent to J. J. Sullivan, No. 777,564, dated December 13, 110

1904. This work-holder, as modified, may conveniently be utilized to hold the article and fabric in their different relative positions during the attaching operation. In 5 the present instance the work-holder comprises the fabric-supporting plate 2 and overhanging clamping levers 3, 4, formed with clamping feet 5, 6, in which are journaled the cylindrical shanks 7, 8, of special 10 hook clamping jaws 9, 10, having their opposed faces grooved at 11, 11, to grip the lateral edges of the bill of a garment hook.

In accordance with the proposed method the hook *h* is first held with its bend adjacent 15 to the fabric and with its throat opening upwardly away from the fabric. The hook and fabric may be readily held in the above described relative positions by placing the fabric between the plate 2 and clamping feet 20 5, 6, and by placing the hook-bill in the grooves 11, 11, of the clamping jaws 9, 10, which may be turned to the position shown in Fig. 3.

The fastening inserting implement, such 25 as the thread-carrying needle 12, coöperating with a suitable loop-taker 12^a, is caused to descend at the point *a* and form an initial fastening stitch forwardly of the bend of the hook. The needle is next caused to penetrate 30 the fabric alternately at opposite sides of the bend of the upturned hook, (Fig. 3), and form a group of stitches *b* closely about the hook-shank at the bottom of the throat, carrying the thread directly into the throat 35 of the hook and into the fabric. The hook is next turned about the stitches *b* as a hinge to place the back of the hook against the fabric, a step which may be performed, for example, by rotating the clamping jaws 9, 40 10, a quarter of a turn. The needle is next caused to form an intermediate stitch at the point *a* and then to form a group of stitches *d*, passing the thread through the eyes of the hook and into the fabric as shown in 45 Fig. 4. If desired one or more final or tying stitches may be formed by the needle at the point *a* for the purpose of securely anchoring the thread end.

The present method is not limited to the 50 attachment of garment-hooks to fabrics but may be advantageously employed in attaching various other articles of irregular shape to fabrics, as will be obvious to those skilled in the art from the foregoing disclosure.

55 Having thus set forth the nature of the invention, what I claim herein is:—

1. The improved method of attaching articles to fabrics which consists in supporting the article close to the fabric, passing fastening means about a localized portion of the article and into the fabric, relatively swinging the article and fabric about said fastening means as a hinge, and passing additional fastening means about another localized portion of the article and into the 60 65 70 75 80 85 90 95 100 105 110 115 120 125 130

fabric, whereby to fixedly secure the article to the fabric at two spaced points.

2. The improved method of attaching garment hooks or the like to fabrics which consists in supporting the hook with its bend adjacent to the fabric and its throat directed at an angle to the fabric, passing fastening means about the bend of the hook and into the fabric, relatively swinging the hook and fabric about said fastening means as a hinge, and passing additional fastening means about a portion of the hook spaced from the bend and into the fabric, whereby to fixedly secure the hook to the fabric at two spaced points.

3. The improved method of attaching hook fasteners to fabrics which consists in supporting the hook with its bend adjacent to the fabric and its throat directed at an angle to the fabric, passing fastening means directly into the throat of the hook and into the fabric, relatively rotating the hook and fabric to position the eyes adjacent the fabric, and passing additional fastening means through the eyes and into the fabric.

4. The improved method of attaching hook fasteners to fabrics which consists in supporting the hook with its bend adjacent to the fabric and its throat directed at substantially right angles to the surface of the fabric, passing fastening means into the fabric in a direction substantially normal to the fabric and directly into the upwardly directed throat of the hook, relatively rotating the hook and fabric to position the eyes adjacent the fabric, and passing additional fastening means through the eyes and into the fabric.

5. The improved method of attaching hook fasteners to fabrics which consists in supporting the hook with its bend adjacent to the fabric and its throat opening in a direction at an angle to the fabric, passing stitches of thread directly into the throat of the hook and into the fabric, relatively rotating the hook and fabric to position the eyes adjacent the fabric, and finally passing additional stitches through the eyes and into the fabric.

6. The improved method of attaching hook fasteners to fabrics which consists in supporting the hook with its bend adjacent to the fabric and its throat opening in a direction at an angle to the fabric, passing stitches of thread directly into the throat of the hook and into the fabric, relatively rotating the hook and fabric to position the eyes adjacent the fabric, and finally passing additional stitches of the same thread through the eyes and into the fabric.

7. The improved method of attaching hook fasteners to fabrics which consists in supporting the hook with its bend adjacent to the fabric and its throat opening in a direction at an angle to the fabric, passing

stitches of thread directly into the throat of the hook and into the fabric, relatively rotating the hook and fabric to position the eyes adjacent the fabric, passing additional 5 stitches of the same thread through the eyes and into the fabric, and finally forming a plurality of tying stitches at a point outside of the eyes.

8. That method of securing a hook to a 10 fabric which consists in sustaining a hook

with its bend adjacent a fabric and with its shank approximately at right angles with said fabric, sewing stitches across said bend, swinging said hook flatwise of said fabric and sewing stitches embracing a portion of 15 the hook spaced from said first stitches.

In testimony whereof I have signed my name to this specification.

WILLIAM L. BARRON.
